UNITED STATES PATENT OFFICE.

JOHN CESERANI, OF BUTTE, MONTANA, ASSIGNOR OF ONE-THIRD TO GEORGE WRIGHTSON, AND ONE-THIRD TO FRANK W. CARPINO, BOTH OF BUTTE, MONTANA.

SURVEYOR'S INSTRUMENT AND RANGE FINDER.

1,406,150.

Specification of Letters Patent. Patented Feb. 7, 1922.

Application filed November 8, 1919. Serial No. 336,620.

To all whom it may concern:

Be it known that I, JOHN CESERANI, a citizen of the United States, residing at Butte, in the county of Silverbow and State of Montana, have invented new and useful Improvements in Surveyors' Instruments and Range Finders, of which the following is a specification.

My invention relates to improvements in 10 surveyors' instruments and range finders.

An important object of the invention is to provide apparatus of the above mentioned character, which is extremely simple in construction, and easy to operate without the 15 employment of complex mathematical rules.

A further object of the invention is to provide apparatus of the above mentioned character, which is free from errors in the results of its operation, which errors would 20 be caused by improper construction of the parts thereof.

A further object of the invention is to provide a plumb level attachment which serves to determine easily and accurately the 25 amount of elevation or depression from the horizontal, of any stated point.

Other objects and advantages of the invention will be apparent during the course of the following description.

30 In the accompanying drawings forming a part of this specification, and in which like numerals are employed to designate like parts throughout the same,

Figure 1 is a plan view of apparatus embodying my invention,

Figure 2 is a perspective view of an angularly adjustable support or base,

Figure 3 is a side elevation of the apparatus showing the telescopes angularly arranged,

Figure 4 is a similar view at a right angle to the showing in Figure 3, with the telescopes parallel,

Figure 5 is a perspective view of the lower base and associated elements, parts being omitted, and,

Figure 6 is a similar view of the adjustable telescope support or bracket.

In the drawings, wherein for the purpose 50 of illustration is shown a preferred embodiment of my invention, the numeral 10 designates a main or lower base, which is pref-

erably in the form of a flat plate. This plate is provided upon its upper surface with four points A, B, C, and D, providing lines arranged at a right angle to each other and forming a square. For the purposes of illustration, it will be assumed that the line A—B is 12 inches in length, but it is obvious that it may be in any multiple of 12 or in any other suitable length.

The numeral 11 designates a support, stand or bracket, which is rigidly secured to the main base 10 and is vertical. The stand or support 11 is arranged in the line A—B so that its central vertical longitudinal axis coincides with the line A—B. This stationary bracket is provided at its upper edge with a sighting instrument or telescope 12, rigidly secured thereto. This telescope is parallel with the base 10 and has its central vertical longitudinal axis coinciding with the line A—B.

The numeral 13 designates an upper base, support or plate, which is angularly adjustable and is parallel with the base 10, upon which it is slidably mounted. The base 13 is preferably rectangular and is provided at one corner with an apertured knuckle 14 pivotally receiving a stationary pin 15, concentric with the point A. This pivotal connection is such that the inner edge of the base 13, when the same is closed, is adapted to contact with the side of the stand 11. The edges 16 will then be at a right angle to the stand 11.

Secured to the upper surface of the base 13 are guides 17, which are parallel with the edges 16, and hence at a right angle to the stand 11, when the base 13 is in the closed position. A carriage 18 is slidable between the guides 17 and an adjustable stand 19 is rigidly secured to the carriage 18 and is vertically arranged or perpendicular to the carriage 18. A sighting instrument or telescope 20 is rigidly secured to the upper end of the stand 19 in parallel relation to the base 13 and having its longitudinal axis disposed at a right angle to the edges 16 or parallel to the longitudinal axis of the instrument 12, when the base 13 is in the closed position.

A scale of measurement 17' is provided, as shown in Figure 1, graduated in any desired fraction of an inch or other suitable

unit of measurement (not shown), by which the telescope 20 may be set at any suitable unit of measurement, in order that the computing of the distance of the object from the sight B, in the manner hereinafter described, can be more accurately determined.

The base 13 is provided at one corner with a fixed point 21, to coat with a scale 22, preferably graduated in fractions of an inch, 10 such as sixteenths of an inch, but can be graduated in any smaller fraction desired, in order to insure greater accuracy, and this scale measures the distance in a straight line from the point B to the point 21. Of course, 15 this scale may be graduated in any other suitable system of measurement, to determine the amount of offset from the point of measurement at B to the point 21.

As more clearly shown in Figure 3, the 20 stand 11 is provided with a segmental opening 23, receiving a plumb level 24, pivoted at 25. This plumb level has its free end operating in proximity to a scale 26, which may be graduated in inches and sixteenths 25 thereof, or in any smaller fraction of an inch desired, in order to insure greater accuracy. For the purpose of illustration it is assumed that the plumb level is set upon a twelve-inch base, and if it should show a departure 30 from the horizontal of one-sixteenth of an inch, the same would mean that in every foot of base the departure from the horizontal is one-sixteenth of the 12-inch or in a distance of 500 feet the offset from the 35 horizontal would be $\frac{1}{16}$ of 500 feet which is $31\frac{1}{4}$ feet.

As an illustration of the operation of the apparatus, it will be assumed that the base 13 is arranged at the point on the scale 22 40 which is $\frac{1}{16}$ of an inch between the point B and the point 21, and that the telescope 20 is arranged at the one-inch point of the scale 17'. It is now desired to determine the distance between the point B and the 45 object in the distance, which occurs at the point of intersection of the sight lines through the telescopes. As the line A—B is 12 inches long, the distance is computed by multiplying 12 by 16, which equals 192 50 inches or 16 feet between the object and the point B. If the telescope 20 were shifted to the two-inch point upon the scale 17' this distance would be 32 feet, and so on. It is thus apparent that the instrument is simplified in operation as the line A—B is 12- 55 inches in length, whereby the distance in feet between the object and the point B may be obtained by multiplying the offset in inches with the length through which the 60 telescope 20 moves, in inches.

It is obvious that this operation is given solely for the purpose of illustration, and that the instrument may be constructed in various sizes and adapted to measure various distances, as may be found advanta-

geous. It is also to be understood that various changes in the shape, size, and arrangement of parts may be resorted to without departing from the spirit of my invention, or the scope of the subjoined claims. 70

Having thus described my invention, I claim:—

1. In an instrument of the character described, a base provided with spaced points forming a line having a selected length, a 75 sighting instrument arranged above the base and connected therewith and having its longitudinal axis coinciding with said line, an upper base having a pivot which is concentric with one end of said line, said upper base having edges thereof adapted to be arranged at a right angle to the longitudinal axis of the sighting instrument when in the closed position and at an angle thereto when in the open position, the first named 80 base being provided with a scale to indicate the extent of movement of the upper base from the other end of the line, said scale being in fractions of the unit of measure of said line and coacting with a portion of said 85 upper base, a carriage arranged upon the upper base, guide means for the carriage extending parallel with the transverse axis of the upper base, and a sighting instrument connected with the carriage and having its longitudinal axis coinciding with the longitudinal axis of the carriage, said guide means being in fractions of the unit of measure of the carriage. 90

2. In an instrument of the character described, a base provided with spaced points forming a line which is 12 inches in length, a sighting instrument arranged above the base and connected therewith and having its longitudinal axis coinciding with said line, 105 an upper base having a pivot which is concentric with one end of said line, said upper base having its transverse axis adapted to be arranged at a right angle to the longitudinal axis of the sighting instrument 110 when the upper base is in the closed position, the lower base being provided with a scale at the other end of said line, such scale being in the fraction of inches and cooperating with the inner edge of the upper 115 base to measure distance between it and such end, the upper base being provided with guide means arranged parallel to the transverse axis thereof, said guide means having a scale in inches and fractions thereof, a carriage 120 slidably engaging the guide means, and a sighting instrument connected with the carriage and having its longitudinal axis disposed at a right angle to the transverse axis of the upper base. 125

3. In an instrument of the character described, a base, a sighting instrument connected therewith, an upper base arranged upon the first named base and adapted to be angularly adjusted with relation to the 130

sighting instrument, and a second sighting instrument carried by the upper base and adapted to be shifted transversely thereof.

4. In an instrument of the character described, a base, a stand secured to the base and provided with a segmental opening and having a scale near the curved portion of the opening, a sighting instrument carried by the stand, an upper base pivoted to the

10 lower base to be angularly arranged with relation to said stand, a carriage adjustably

mounted upon the upper base to be shifted transversely thereof, and a second sighting instrument secured to the carriage, and means suspended upon the stand and operating within the scale opening to determine the deviation from the horizontal to permit of correction of the error of the findings of the sighting instruments due to the deviations from the horizontal. 15

JOHN CESERANI.
